UNITED STATES PATENT OFFICE.

HOMER ARTHUR KING, OF COLTON, CALIFORNIA.

ROTARY ENGINE.

1,076,891.

Specification of Letters Patent.

Patented Oct. 28, 1913.

Application filed January 23, 1913. Serial No. 743,856.

To all whom it may concern:

Be it known that I, HOMER ARTHUR KING, a citizen of the United States, residing at Colton, in the county of San Bernardino and State of California, have invented a new and useful Rotary Engine, of which the following is a specification.

This invention relates to the art of engines, and more especially to the rotary type, preferably using steam as the motive power.

An object of the invention is to provide a multiple cylinder engine, more particularly for use upon sea-going vessels, and constructed in such wise as to propel one or more propellers in opposite directions. Owing to the propellers moving in opposite directions, thereby acting against opposing currents, considerable power is produced.

20 A further object of the invention is to improve and simplify the structures disclosed in the Letters Patents, dated November 28, 1911; Serial No. 1,010,378; and December 10, 1912, Serial No. 1,046,607.

25 In practical fields it may be found necessary and desirable to subject the minor details of construction of the present engine to alterations, to which the patentee is entitled, provided the alterations fall within the scope of what is claimed.

The invention comprises further features and combination of parts, as hereinafter set forth, shown in the drawings and claimed.

35 In the drawings:—Figure 1 is a longitudinal sectional view through the improved multiple cylinder engine, showing the same adapted for propelling two or more propellers in opposite directions. Fig. 2 is an enlarged sectional view on line 2—2 of Fig. 1. Fig. 3 is an enlarged sectional view on line 3—3 of Fig. 1. Fig. 4 is an enlarged cross sectional view on line 4—4 of Fig. 1. Fig. 5 is a sectional view through one of the abutments, showing the retention rings in the packing rings. Fig. 6 is a sectional view on line 6—6 of Fig. 5. Fig. 7 is a detail view of one of the disk valves.

40 Referring more particularly to the drawings, 1 designates the casing of a multiple cylinder engine, which is provided with a plurality of steam chambers 1^b, while 1^c denotes a plurality of rotors, each having pistons 15, upon opposite sides, adapted to move in the steam chamber 1^b. The rotors are provided with exhaust ports 12, through

which the utilized steam exhausts, in order to aid the usual exhaust ports 13.

This improved engine is provided with two propelling shafts, a hollow shaft 2^a, 60 and a solid shaft 2, which telescopes through the hollow shaft 2^a; there being a propeller 33 movable with the shaft 2^a, and a similar propeller 32 movable with the shaft 2. The rotors of two of the cylinders rotate with the hollow shaft 2^a, as at 2^b, while the rotors of the other two cylinders rotate with the solid shaft 2. The ports 12 of two of the rotors merge into the passages 12^a, while the ports 12 of the other two rotors merge into the passages 12^c. Constructed between the cylinders are steam chests 7, into which steam is admitted by way of the inlet pipe 9. The steam from the chests is admitted to the steam chambers 1^b by way of the ports 70 10. The ports 10 of every other cylinder are arranged at right angles. Arranged in the steam chests are disk valves 37, there being a pair in each chest, one pair movable with the solid shaft at 37^a, while the other pair is keyed at 37^b to the hollow shaft. It is to be remembered that there are four rotors, two traveling in one direction and acting to rotate the solid shaft, while the other two rotate in the opposite direction, and act to 85 rotate the hollow shaft; and as said shafts rotate the openings 10^b of the disk valves 37 register with the ports 10 at intervals, thereby admitting steam from the steam chests into the steam chamber 1^b so as to 90 act upon the pistons 15. Surrounding the hollow shaft and the solid shaft are coil springs 10^b interposed between the disk valves 37 to hold them closely in contact with the set plate valves 8. The steam in the steam chests also act to hold the disk valves closely in contact with the set plate valves 8, which are in turn held in close contact with the cylinder casings by the steam. The set plate valves are provided with segmental slots 8^a, which register with the ports 10, which registration, together with the registration of the openings 10^b with the slot ports 8^a allows steam from the chests to enter the steam chambers 1^b, by 95 way of the ports 10. Stop lugs 28 project from the cylinder casings through the segmental slots 8^a, in order to limit the set plate valves in one direction or the other. These set plate valves do not rotate with the shafts, but are adjustable independent 100 of the shaft and relative to the disk valves

especially their ports 10^b, by virtue of the gears 29 and the levers 30, the teeth of which gears 29 mesh with the teeth of the set plate valves 8. By virtue of the levers 30 and the 5 gears 29, the set plate valves in their positions may be regulated for a variable portion of the travel of each piston, by direct pressure of steam, that is, as each piston travels from each steam inlet, while steam 10 expansion moves each piston toward each steam exhausts 13 for the remaining variable portion of the piston's travel.

Each cylinder is provided with two offset casings 27^a arranged opposite one another. Each pair of offset casings 27^a of one cylinder is arranged at right angles to the offset casings of the adjacent cylinder. Mounted to rock in the offset casings 27^a are members 18 having arms 19 movable therewith. Projecting radially from the members 18 are arms 18^a, to which segmental arms 18^b are connected. These offset casings 27^a not only include the segmental passages 27^b, in which the abutments 16 are 20 movable, but also include the exhaust ports 13, which are concentric with the passages 27^b. The exhaust ports 13 are utilized for the exhaust of the greater part of the utilized steam, while the exhaust ports 12 are auxiliary, and are designed to aid in carrying off the remainder of the utilized steam. The segmental passages 27^b merge into the steam chamber, so that the abutments will drop or fall in the rear of the pistons immediately and instantly after the pistons pass. The abutments 16 comprise the disks 16^b and 16^k, the disks 16^b are pivoted loosely to the segmental arms 18^b, as at 16^m, while the disks 16^k are provided with openings 30 16^a, through which the segmental arms 18^b extend. Extending around the periphery of the disks 16^b and 16^k are expansion rings 16^a. In other words, these packing rings 16^a are split as shown at 16^g, so as to expand against 40 the retention rings 16^s, which lessens the force of the expansion packing rings 16^a in contacting with the walls of the segmental passages 27^b. In different words, the retention rings 16^s prevent too much expansion of the split expansion packing rings 16^a, so that they may freely pass from the 45 passages 27^b into the cylinder. Interposed between the expansion packing rings 16^a are similar rings, which are also adapted to expand, and are provided with grooves in which retention rings 16^s are arranged. Extending transversely of the arms 18^b and fixed in place in any suitable manner (not shown) are leaf springs 18^b, the ends of which bear 50 against the disks 16^k, so as to hold the expansion rings in place. It will be noted by referring to Fig. 5 that the openings 16^a of the disks 16^k are of such contour as to permit the disks 16^k to rock, which together 55 with the pivotal connection 16^m between the

arm 18^b to the disk 16^b, will permit the abutment 16, as it moves in its passage-way to conform to the contour, especially where the passage-way merges into the steam chamber.

The pistons 15 are designed to include 70 expansion packing rings similar packing rings 16^a of the abutments having grooves in which retention rings similar to the retention rings 16^s are arranged, but are not particularly shown. The rings (which are 75 similar to the rings 16^s) of the pistons prevent too much expansion of the split packing rings (which are similar to the split expansion packing rings 16^a) of the pistons, so that they may freely pass the enlarged 80 portions of the cylinder. Furthermore, by such expansion packing rings and the retention rings steam tight joints between the abutments and the passage-ways 27^b and between the pistons and the walls of the steam chamber are provided. At the point where the segmental arms 18^b pass through the walls 27^c of the offset casings 27^a, packing 85 27 is arranged.

Referring to Fig. 3 of the drawings there 90 is a head member 22 keyed to one of the shafts, say for instance, the solid shaft, so as to revolve therewith. Each arm of this revolving head member is provided with an anti-frictional member 23 to engage the segmental or curved portion of each lever 25, which is pivoted at 25^a to the cylinder casings. The curved extension 25^b of each lever 25 is provided with a link connection 20 with one of the arms 19 of each member 18, 100 while the other arm 19 of each member 18 has a link connection 19^a to it. Each link 19^a is in turn pivoted to a short curved lever 26, also pivotally mounted at 25^a. The levers 25 and 26 have link connections 21, so that 105 as one of the anti-frictional members or wheels 23 oscillates one of the levers 25, one of the short levers 26 is oscillated in unison, and vice versa. As the head member 22 revolves, the levers 25 and 26 are in turn 110 actuated, in order to rock the members 18. When the members 18 are rocked, the abutments are moved through the passages 27^b, and into and from the path of the traveling pistons 15. The object in providing the 115 form of abutments as shown in Fig. 5, is to permit them to accommodate themselves to the passage-ways 27^b and the curvature of the steam chambers.

In the operation of this improved 120 multiple cylinder engine, steam from the steam chest enters the steam chamber 1^b, by way of the ports 10, thereby acting upon the pistons. It will be seen that the pistons, the rotors, and either the solid or hollow shaft 125 rotate as one body, and being that the head member 22 is movable with each shaft, the abutments are withdrawn from the path of the pistons, upon their approach upon the abutments, through the medium of the lever 130

and link connections between the head member 22 and the rocking members 18. As the pistons pass the abutments, they are again lowered within the steam chambers.

5 The utilized steam exhaust through the ports 13, but the exhaust of this steam is aided, considerably, owing to the provision of the ports 12^a and 12^c, through the rotors and the shaft.

10 The outer walls of the steam chambers, at the point where the pistons closely approach the abutment in their travel, are offset or spaced apart from the pistons, as at 1^e, so as to lessen the friction, thereby allowing 15 the pistons to move more freely, as there is hardly any steam pressure at this point. The springs 10^b are utilized more especially, when no steam pressure exists. Between the rotors and the cylinder casings inclined 20 packing rings 14^a are provided, which packing rings 14^a are also designed to have retention rings (similar to the retention rings 16^b) but not particularly shown, so as to prevent too much expansion of the rings 14^a.

25 From the foregoing it is to be noted that there has been devised a simple and efficient multiple cylinder engine, more especially adapted for operating propellers in opposite directions, so as to act against opposing currents, in order to drive sea-going vessels at considerable speed, and one which has been found practical.

The invention having been set forth, what is claimed as new and useful is:—

35 1. In a rotary engine having a rotor provided with substantially oppositely arranged pistons, a casing inclosing said rotor and having an annular steam chamber in which the pistons operate, said casing having offset casings, rocking members mounted in said offset casings and provided with radially extending arms terminating in segmental curved arms concentric with said rocking members, the offset casings having 40 segmental passage-ways merging into the steam chamber, piston-like abutments movable in the segmental passage-ways and comprising spaced apart disks, one disk of each abutment being pivoted to each segmental curved arm, said disks having shoulders, split expansion packing rings surrounding said disks and in contact with said shoulders and provided with channel-ways, extension rings in said channel-ways, a series 45 of annular split expansion packing rings interposed between the expansion rings of said disks and provided with retention rings to limit the expansion of the split rings, means bearing against one disk of each abutment for pressing said disk toward the pivoted disk to hold the intermediate expansion rings in place, said abutments adapted to follow in the rear of said pistons and partially into the steam chamber, and means 55 for operating said rocking members.

2. In a rotary engine, a cylinder casing provided with an annular steam cylinder having enlarged portions, a rotor movable in the steam cylinder and having pistons provided with channeled split piston packing rings, expansion-limiting channeled rings therefor, which together with the enlarged portions of the annular steam cylinder renders the easy passage of the pistons during the movements of the abutments, a shaft for the rotor, said casing including offset casings having segmental curved passages merging into the steam cylinder, abutments movable in the passages, said abutments comprising spaced apart disks, one disk of each abutment being pivoted to each segmental curved arm, said disks having shoulders, split expansion packing rings surrounding said disks and in contact with said shoulders and provided with channel-ways, rings in said channel-ways, a series of annular split expansion packing rings interposed between the expansion packing rings of said disks and provided with rings to limit the expansion of the split rings, means bearing against one disk of each abutment for pressing said disk toward the pivoted disk to hold the intermediate expansion rings in place, and connections between the shaft and said abutments to cause said abutments to follow at intervals in the rear of said piston as they pass.

3. In a multiple cylinder rotary engine, a plurality of casings having a solid shaft and a hollow shaft extending therethrough, said solid shaft having a portion of its length received by the hollow shaft, said casings having steam chambers, rotors mounted upon the shafts and provided with pistons movable in the chambers, steam chests interposed between the casings, ports of communication between the chests and steam chambers, set plate valves, two mounted upon the hollow shaft and two upon the solid shaft to control the steam through said ports, disk valves acting in conjunction with set plate valves to facilitate controlling of said steam, two of the disk valves mounted upon the hollow shaft, and two upon the solid shaft, coil springs, one surrounding the hollow shaft and the other surrounding the solid shaft, to hold the disk valve separated and in contact with the plate valve, means for manually adjusting the plate valves relative to the disk valves, said casings having offset casings provided with curved passage-ways, abutments operable in the curved passage-ways, and connections between said shaft and said abutment, and exhaust ports in the offset casings.

4. In a multiple cylinder rotary engine, a plurality of casings having a solid shaft and a hollow shaft extending therethrough, said solid shaft having a portion of its length received by the hollow shaft, said casings

having steam chambers, rotors mounted upon the shafts and provided with pistons movable in the chambers, steam chests interposed between the casings, ports of communication between the chests and steam chambers, set plate valves, two mounted upon the hollow shaft and two upon the solid shaft to control the steam through said ports, disk valves acting in conjunction with set plate valves to facilitate controlling of said steam, two of the disk valves mounted upon the hollow shaft, and two upon the solid shaft, coil springs, one surrounding the hollow shaft and the other surrounding the solid shaft, to hold the disk valve separated and in contact with the plate valve, means for manually adjusting the plate valves relative to the disk valves, said casings having offset casings provided with curved passage-ways, abutments operable in the curved passage-ways, said abutments comprising spaced apart disks, one disk of each abutment being pivoted to each segmental curved arm, said disks having shoulders, split expansion packing rings surrounding said disks and in contact with said shoulders and provided with channel-ways, rings to limit the expansion of split rings in said channel-ways, a series of annular split expansion packing rings interposed between the expansion rings of said

disks and provided with rings to limit the expansion of the split rings, means bearing against one disk of each abutment for pressing said disk toward the pivoted disk to hold the intermediate expansion rings in place, 35 and connections between said shafts and said abutments to cause the abutments to follow at intervals in the rear of the pistons.

5. In a rotary engine, a casing provided with a steam chamber, a rotor having sectional pistons movable in the steam chamber, a shaft for the rotor, said casing having offset casings provided with segmental passage-ways merging into the steam chamber, sectional abutments movable in the passage-ways to accommodate themselves to the contour of said passage-ways, said sectional abutments and sectional pistons having expansion packing rings provided with rings to limit the expansion of the split rings, and 50 connections between said shaft and said abutments.

In testimony whereof I have signed my name to this specification in the presence of two subscribing witnesses.

HOMER ARTHUR KING.
